UNITED STATES PATENT OFFICE.

WILLIAM A. WEBSTER, OF MANCHESTER, NEW HAMPSHIRE.

UMBRELLA.

SPECIFICATION forming part of Letters Patent No. 341,192, dated May 4, 1886.

Application filed August 3, 1885. Serial No. 173,380. (No model.)

To all whom it may concern:

Be it known that I, WILLIAM A. WEBSTER, of Manchester, county of Hillsborough, and State of New Hampshire, have invented an improvement in Umbrellas, of which the following description, in connection with the accompanying drawings, is a specification, like letters on the drawing representing like parts.

10 This invention has for its object to provide an umbrella which can be folded into small compass for convenience of travelers, &c.

The invention consists in the combination, with the umbrella-stick and the usual fixed and running sleeves, of a series of compound levers or lazy-tongs of peculiar construction, as will be hereinafter more fully described, said compound levers or lazy-tongs radiating from the sleeves and serving to support the 20 cover which is attached thereto.

The drawing shows in section an open umbrella constructed in accordance with this invention, the stick being shown in elevation.

The stick *a*, fixed sleeve *b*, and running sleeve *c* are all as usual, so need not be herein described.

The running sleeve *c* is connected with the fixed sleeve *b* by compound levers or lazy-tongs, the first pair, *f g*, of which are pivoted to the sleeves *b c*, respectively, by wires *e*, passing through the ends of the said levers and around the sleeves, or in any other usual manner, the said levers being pivoted together by a pivot, 2. The succeeding pair of 30 levers, *h i*, pivotally connected, respectively, to the opposite ends of the first pair of levers, *f g*, are made shorter than the first pair, to thus give to the cover *f'* (shown in dotted line) sufficient incline, and are pivoted together at 35 3. The final pair of levers, *m n*, are pivotally connected with the preceding pair of levers, *h i*, by pivots 7 8, the lever *n* being connected with the central part of the prolonged lever *m* at the pivot 4. The final pair of levers, 40 constructed substantially as shown and described, gives to the cover *f'* a further incline.

The compound levers or lazy-tongs consist of as many pairs of levers as desired, care be-

ing taken that each succeeding pair leading from the sleeves is made shorter, to give 50 ample slope or incline to the cover *f'*.

The series of compound levers or lazy-tongs pivotally connected with the sleeves, as described, and leading therefrom radially, support a cover, *f'*, said cover being secured to 55 the fixed sleeve *b* in any usual manner, and spread and attached to the uppermost ends of the levers, as at 7, and to the free ends of the prolonged levers *m*.

The drawing shows the levers extended and 60 the umbrella spread; but by running the sleeve *c* downward the levers are drawn together into compact body, thus permitting an umbrella of large diameter to be closed in very compact form.

65 The handle *a* is preferably short, so that when the umbrella is closed it may be put in any ordinary valise.

The invention is equally applicable to parasols, and for ladies may be found very convenient.

I do not broadly claim the application of lazy-tongs to umbrellas and the like, instead of rigid stretchers, for such I know to be older than my invention.

75 I claim—
As an improved article of manufacture, an umbrella or parasol consisting of a stick, fixed and running sleeves mounted thereon, and a series of compound levers or lazy-tongs connecting the said sleeves and leading therefrom radially, each pair of levers of the compound levers or lazy-tongs being made shorter than the preceding pair, and the final pair of levers consisting of a prolonged lever and a short 80 actuating-lever, and a cover, *f'*, spread over and attached to the series of compound levers, all substantially as and for the purpose described.

85 In testimony whereof I have signed my name to this specification in the presence of two subscribing witnesses.

WILLIAM A. WEBSTER.
